DESIGN.

—o—

E. L. JENKINS.

SLEEVE.

No. 18,478.

Patented July 24, 1888.

UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A SLEEVE.

SPECIFICATION forming part of Design No. 18,478, dated July 24, 1888.

Application filed June 15, 1888. Serial No. 277,269. Term of patent 3½ years.

To all whom it may concern:

Be it known that I, ETTA L. JENKINS, of the city, county, and State of New York, have invented and produced a new and original Design for a Pattern of a Lady's Sleeve; and I do hereby declare that the engraved prints accompanying this specification convey to any one accustomed to using paper patterns a clear understanding of how a garment made up by the pattern will appear.

The design shows a coat-sleeve that displays a short full puff above a deep smocked band and a long full puff extending from the smocked band to within several inches of the wrist-edge. 15

What I claim as my invention, and desire to secure by Letters Patent, is—

The design for a lady's sleeve, as shown in the engraved prints accompanying this specification.

ETTA L. JENKINS.
